[57] CLAIM

The ornamental design for a chair, substantially as shown and described.

DESCRIPTION

FIG. 1 is a frontal perspective view of a chair made in accordance with my design;

FIG. 2 is a front elevational view of the chair;

FIG. 3 is a side elevational view of the chair;

FIG. 4 is a rear elevational view of the chair;

FIG. 5 is a top plan view of the chair;

FIG. 6 is a bottom plan view of the chair; and

FIG. 7 is a generally rear perspective view of the chair.

The chair is characterized by a continuous swept-back tubular frame comprised of upwardly and rearwardly extending leg support members which extend at the same angle as paired back rest support members in combination with a back rest cushion being supported on the vertically extending back rest support members and being parallel both thereto and to the leg support members, all as best shown in FIGS. 3 and 7.

FIG. 1.**FIG. 2.****FIG. 3.**

FIG.4.**FIG.5.****FIG.7.****FIG.6.**
